UNITED STATES PATENT OFFICE.

HERMAN KAHN, OF TROY, NEW YORK.

DESIGN FOR A LOCK-BAR FOR COVERS.

SPECIFICATION forming part of Design No. 30,411, dated March 28, 1899.

Application filed March 1, 1899. Serial No. 707,401. Term of patent 7 years.

To all whom it may concern:

Be it known that I, HERMAN KAHN, of Troy, in the county of Rensselaer and State of New York, have invented and produced a new and original Design for a Lock-Bar for Covers, of which the following is a full, clear, and exact description.

The design relates to lock-bars for the closures of jars and like vessels.

Reference is to be had to the accompanying drawing, forming a part of this specification, which is a perspective view of the lock-bar in different positions.

The design in its entirety comprises the body *a*, having at its ends lips *b b*, the lips decreasing in thickness in opposite directions from one side edge, spaced projections *c c*

rising from the upper face, and a circular orifice *d* appearing in the body *a* at the center between the projections, and the body being increased in width at the center, the widened portion presenting rounded lines at the side edges.

The essential feature of the design consists in the body, having at its ends lips decreasing in thickness in opposite directions, and projections rising from the upper face of the body.

I claim—

The design for a lock-bar for covers herein shown and described.

HERMAN KAHN.
